CLAIM

The ornamental design for a light fixture element, as shown
and described.

DESCRIPTION

FIG. 1 is a front view of the light fixture element;

FIG. 2 is a left side view of the light fixture element, wherein
the right side view is a mirror image thereof;

FIG. 3 is a top view of the light fixture element;

FIG. 4 is a bottom view of the light fixture element; and,

FIG. 5 is a back view of the light fixture element.
